CLAIM

The ornamental design for an ice maker, as shown and described.

DESCRIPTION

The patent or application file contains at least one drawing executed in color. Copies of this patent or patent application publication with color drawing(s) will be provided by the Office upon request and payment of the necessary fee.

1. Ice maker

1.1 : Front

1.2 : Back

1.3 : Left

1.4 : Right

1.5 : Top

1.6 : Bottom

1.7 : Perspective

The use of the present design product; the design product is used for making ice; The design gist of the present design

(Continued)

product: the overall shape; The picture or photo best showing the design gist of the present design product: perspective view.

1 Claim, 7 Drawing Sheets
(7 of 7 Drawing Sheet(s) Filed in Color)
